UNITED STATES PATENT OFFICE.

JOHN KERR, OF DETROIT, MICHIGAN, ASSIGNOR TO THE DETROIT DENTAL MANUFACTURING COMPANY, OF SAME PLACE.

DESIGN FOR A DENTAL CLASP.

SPECIFICATION forming part of Design No. 22,668, dated August 1, 1893.

Application filed June 5, 1893. Serial No. 476,678. Term of patent 7 years.

To all whom it may concern:

Be it known that I, JOHN KERR, a citizen of the United States, residing in Detroit, county of Wayne, and State of Michigan, have invented and produced a new and original Design for Dental Clasps, of which the following is a specification, reference being had to the accompanying drawings, in which—

- Figure 1 is a perspective view of my clasp.
10 Fig. 2 is a side elevation thereof.
This design consists of the body portion A, curved and gradually narrowing toward the

lower end, forming the back and lower limb of the clasp, and the straight horizontal extension B forming the upper limb of the clasp 15 extending at an angle from the upper portion of the body A.

What I claim as my invention is—

The design for a dental clasp substantially as herein shown and described.

JOHN KERR.
